DESIGN FOR A BOTTLE

Gerald J. Graham, Chicago, Ill.

Application April 20, 1934, Serial No. 51,471

Term of patent 7 years

To all whom it may concern:

Be it known that I, GERALD J. GRAHAM, a citizen of the United States, residing at Chicago, in the county of Cook and State of Illinois, have invented a new, original, and ornamental Design for a Bottle, of which the following is a specification, reference being had to the accompanying drawing, forming part thereof.

Fig. 1 is a front elevation of the bottle embodying my design;

Fig. 2 is a side elevation of the bottle shown in Fig. 1.

I claim:

The ornamental design for a bottle, as shown.

GERALD J. GRAHAM.
